Primary Examiner — Angela J Lee*Assistant Examiner* — Audris Park(74) *Attorney, Agent, or Firm* — Tsz Lung Yeung(57) **CLAIM**

The ornamental design for a magnifier with lighting arrangement, as shown and described.

DESCRIPTION

FIG. 1 is a perspective view of a magnifier with lighting arrangement showing my new design;

FIG. 2 is a front view thereof;

FIG. 3 is a rear view thereof;

FIG. 4 is a right end view thereof;

FIG. 5 is a left end view thereof;

FIG. 6 is a top view thereof; and,

FIG. 7 is a bottom view thereof.

The broken lines depict portions of the magnifier with lighting arrangement that form no part of the claimed design.
